ATTORNEY

UNITED STATES PATENT OFFICE.

FREDERIC KIEFER, OF CHICAGO, ILLINOIS.

DISPLAY DEVICE.

1,156,603.

Specification of Letters Patent.

Patented Oct. 12, 1915.

Application filed April 25, 1914, Serial No. 834,326. Renewed August 16, 1915. Serial No. 45,822.

To all whom it may concern:

Be it known that I, FREDERIC KIEFER, a citizen of the United States, and a resident of Chicago, in the county of Cook and State 5 of Illinois, have invented certain new and useful Improvements in Display Devices, of which the following is a specification.

This invention relates particularly to a display device on which wringing machines 10 may be placed in a shop, store, or other place where said wringers are to be sold or examined. And the principal purpose of the invention is to obtain a device in which wringers of different sizes may be displayed 15 without adjustment of the device and in which all parts of the wringer may be exposed to view, by turning said wringer about a given point to bring all sides thereof in view of a person standing in front of the 20 device.

Further objects are to obtain a device which is simple in construction, easily understood, not liable to break or get out of order, and readily manipulated.

25 In the drawing accompanying and forming a part of this specification Figure 1 illustrates a device embodying this invention, with a wringer contained thereon, in side elevation. Fig. 2 is a top plan view of the 30 device. Fig. 3 is a side elevation, and Fig. 4 a front elevation of the device. Fig. 5 is a perspective of a pivoted member of the device. Fig. 6 is a top plan view of an engaging member of the device, and Fig. 7 is a 35 horizontal section on line 7-7 of Fig. 3, viewed in the direction indicated by the arrows. Fig. 1 is drawn to a smaller scale than are the remainder of the figures in the drawing.

40 A reference letter applied to designate a given part indicates said part throughout the several figures of the drawing wherever the same appears.

A is the base of the device, and when the 45 device is in use said base is in a substantially vertical position.

B is a table firmly secured to the base A, and in Fig. 3 said table is shown integral with said base.

50 C is a rotatable member pivotally secured on table B by pivot D.

E is a bolt, (which is illustrated with the winged head e), fitting in a screw threaded hole in side C¹ of member C.

C² is a side to member C, substantially 55 parallel to side C¹.

F is a groove on the upper end of base A. Groove F is obtained by the sides f, f, and flanges f¹, f¹.

G is a movable member, which is movable 60 vertically in groove F, and forms what I term a sub-base.

H is an eye-bolt, which is provided with screw threads h fitting into corresponding screw threads in sub-base G. 65

X is a portion of a wall, or post, against which the device is secured by fastenings which extend through the holes Y, (Fig. 4) in base A.

W is a wringer, provided with side posts 70 Z, Z, and adjusting bolts Z¹.

To use the device the bottom of one of the side posts, (Z, Fig. 1), is secured in the rotatable member C, between the sides C¹, C², by turning bolt E firmly against one side 75 of said post, and one of the adjusting bolts Z¹, Z¹, of the wringer (lettered W), is removed from the wringer, extended through the eye of the eye-bolt H, and again put in place in the wringer. 80

In Fig. 1 the wringer which is illustrated is shown in front elevation, with the device shown in side elevation. By moving the side of wringer W which is shown as at the extreme right hand in Fig. 1, said wringer 85 will be turned around the axial line of the pivot D, and either end, as well as the opposite side of said wringer is thereby brought into view.

Groove F forms a guide for the sub-head 90 or movable member G, and the eye bolt H forms a means of attachment to the adjusting screw or bolt of the wringer which is to be displayed in the device. Guide F permits movable member G to be raised and adjusted to different sizes of wringers. 95

I claim,—

In a display device for wringers, the combination of a vertical base provided with a horizontal table and a vertical guide, a pivoted member on said table adapted to support the vertical member of a wringer, means 100

to attach said member thereto, a member adjustably movable vertically in said guide and horizontally adjustable means to attach said movable member to said vertical member of a wringer, said horizontally adjustable attaching means being alinable with said pivoted member, all adapted to hold

said wringer displayed in said device in a vertical position, with said wringer movable in a substantially horizontal plane.

FREDERIC KIEFER.

In the presence of—

CHARLES TURNER BROWN,

CHARLES B. HEBRON.
